UNITED STATES PATENT OFFICE.

HARRY MINTZ, OF BOSTON, MASSACHUSETTS.

FOLDING HAMMOCK-SUPPORT.

1,223,717.

Specification of Letters Patent. Patented Apr. 24, 1917.

Application filed June 17, 1914, Serial No. 845,730. Renewed March 8, 1917. Serial No. 153,459.

To all whom it may concern:

Be it known that I, HARRY MINTZ, a citizen of the United States, and resident of Boston, in the county of Suffolk and State 5 of Massachusetts, have invented new and useful Improvements in Folding Hammock-Supports, of which the following is a specification.

This invention relates to folding frames 10 of the kind used for hammock supports and for similar purposes, and consists principally of a new and improved structure for joining the top bar with the legs, affording a strong and firm structure with a minimum 15 of parts, and capable of being easily set up or knocked down without the manipulation of screws, bolts or other fastening devices.

In the accompanying drawings, which illustrate an embodiment of the invention,— 20 Figure 1 is a perspective view of the frame set up and ready for use;

Fig. 2 is an enlarged side view of one end of said frame;

Fig. 3 is a section on line 3—3 of Fig. 2 25 showing the position of the legs and their clamping members when said frame is set up;

Fig. 4 is a view similar to Fig. 3, showing the position of the legs and their clamping members when said frame is knocked 30 down; and

Fig. 5 is a horizontal section through one end of the top bar, on line 5—5 of Fig. 3.

The top bar *a*, and the legs *b*, may be 35 of ordinary construction, and as herein shown consists of tubular iron. The legs are pivotally connected with the top bar by braces or links *c*, each of which is permanently pivoted at one end to a leg at 40 *c'*, and at the other end at *c''* to the shank *a''* of the hook *h*. At the proper distance from each end of the top bar *a* is a collar *a'*, permanently fastened to the top bar by a rivet *a''* (Fig. 2). The flat shank *a''* 45 extends down from the under side of this collar and terminates in the hook *h*.

At the top of each leg *b* is a casting or clamping member *d*, riveted to the end of the leg, projecting upward and terminating 50 in a semi-cylindrical jaw *e*, or half sleeve. Each of these half sleeves may be plain or may have a pin *e'* on the inner face

fitting into a hole *e''* in the top bar *a* (Fig. 55 4). Each casting *d* has a lug *d'*, through which passes a pivot pin *g*, to permit the legs *b* to be folded together on the pivot pin, by which the two members *d* of each pair are connected. 60

To set up or assemble the device, the legs *b* of each pair, while still folded together, are swung on the link *c* until they are substantially perpendicular to the top bar *a*, as shown in Fig. 4. The legs are 65 then swung apart until the two sleeve sections *e* come together and embrace the end of the top bar as shown in Fig. 3. The legs are held in spread position by the cross bars *l* at the bottom. The sleeve is 70 prevented from slipping lengthwise of the top bar *a* by the pins *e'* on the inside face of each half sleeve. To take down the frame, the legs *b* are folded together, thereby by opening the sleeve, and are then swung 75 parallel to the top bar *a* on the links *c*.

One of the sleeve sections *e* is made at its outer end with a wall *e''*, which not only closes the end of the sleeve formed by the two sleeve sections *e*, *e*, when the frame is 80 set up, and conceals the end of the top bar, but also affords additional security to prevent the sleeve from slipping inward along the top bar. 85

I claim:

A folding frame comprising a top bar, a pair of supporting legs pivoted together near the top and sleeve sections at the top of each pair of legs actuated by the relative movements of said legs and coöperating to 90 embrace the ends of the top bar to unite the legs and top bar when the frame is set up, each of said sleeve sections having a pin on its inner face and each end of the top bar being provided with holes to engage 95 said pin when the sleeve sections are in closed position, one at least of the sleeve sections of each pair being provided with an end wall adapted to overlie the end of the top bar. 100

Signed by me at Boston, Massachusetts, this 15th day of June, 1914.

HARRY MINTZ.
